UNITED STATES PATENT OFFICE.

ROY F. PERKINS, OF MIDDLEBORO, MASSACHUSETTS.

WALL-BRACKET.

1,390,539.

Specification of Letters Patent. Patented Sept. 13, 1921.

Application filed March 23, 1921. Serial No. 454,645.

To all whom it may concern:

Be it known that I, ROY F. PERKINS, a citizen of the United States, and a resident of Middleboro, in the county of Plymouth and State of Massachusetts, have invented 5 certain new and useful Improvements in Wall-Brackets, of which the following is a specification.

This invention relates to improvements in 10 hangers especially adapted for supporting hot water bottles and the like.

An important object of this invention is to provide a hanger for hot water bottles and the like, having novel means whereby the 15 flexible tube of the bottle may be supported in such a manner that it will not crack.

A further object of the invention is to provide a hanger of the character described having a single hook provided at one end 20 with an attaching loop and at its other end with a bill adapted to engage the attaching portion of a hot water bottle or the like.

Other objects and advantages of the invention will be apparent during the course 25 of the following description.

In the accompanying drawing forming a part of this application and in which like numerals are employed to designate like parts throughout the same,

30 Figure 1 is a side elevation of the improved hanger, parts being shown in section,

Fig. 2 is a plan view of the same,

Fig. 3 is a side elevation of the same in 35 use,

Fig. 4 is an end elevation of the same,

Fig. 5 is a vertical transverse sectional view through a block embodied in the invention, and

40 Fig. 6 is a perspective of a hook embodied in the invention.

In the drawing, wherein for the purpose of illustration is shown a preferred embodiment of the invention, the numeral 10 generally designates a body or block which is preferably formed from a single piece of wood or like material and which includes a semi-circular rib 11 and a back 12 with which the semi-circular rib 11 is formed 45 integral. As illustrated in Fig. 5, the intermediate portion of the longitudinally curved reinforcing rib 11 is formed with a transverse opening 14 which receives the shank 15 of a hook generally designated by 50 the numeral 16. The shank 15 of the hook 55

16 is offset intermediate its ends as indicated at 17 and this offset portion 17 contacts with the under side of the laterally projecting semi-circular rib 11 so that the block or body is securely held on the hook. After 60 passing the shank 15 through the opening 14, the end of the shank is formed with a loop 17' by means of which the device may be suspended from a nail or other support.

As illustrated in Fig. 4, the offset portion 65 17 of the shank 15 disposes the lower portion of the shank in advance of or in spaced relation to the back 12 so that the apertured ear 18 of a hot water bottle 19 may be readily and conveniently connected to the bill 20 70 of the hook. It will be noted that the bill 20 of the hook extends slightly below the lower edge of the body so that the hot water bottle may be readily connected to the same.

The rib 11 which projects laterally from 75 the back 12 and forms a shoulder for engagement by the offset portion 17, has its outer side formed with a groove 22 which receives the tube 23 of the bottle 19. By reason of this construction the tube 23 is prevented from cracking intermediate its ends when not in use and when supported as illustrated in Fig. 3.

With reference to the foregoing description it will be apparent that a device 80 constructed in accordance with this invention may be cheaply manufactured and is admirably adapted for supporting hot water bottles and the like.

Having thus described the invention, what 85 I claim is:—

1. A device of the class described comprising a body having a laterally projecting rib constituting a shoulder, a hook having a shank passing through said rib and provided 90 with an offset portion engaging said shoulder.

2. A device of the class described comprising a body having a rib constituting a shoulder, a hook having a shank passing through 100 said rib and provided with an offset portion engaging said shoulder, said rib being of semi-circular formation and provided with a groove for receiving a flexible tube.

3. A device of the class described comprising a semi-circular body having a reinforcing rib constituting a shoulder, an attaching hook having a shank passing through said rib and having an offset portion engaged with said shoulder, said shank 110

being formed with a bill adapted to be engaged by an article, the offset portion of said shank disposing the bill in spaced relation to the body.

5. 4. A device of the class described comprising a semi-circular body having a laterally projecting semi-circular rib provided with an opening, a hook having a shank

provided with an offset portion engaging said rib, said shank being passed through said opening and formed with attaching means, one end portion of said shank being formed with a bill spaced from the body by said offset portion.

ROY F. PERKINS.
